“Viva Collection Blender HR3556/00”; Philips; retrieved Nov. 28, 2018; disclosure date unknown but prior to filing date of present application; URL: <https://www.philips.ae/c-p/HR3556_00/viva-collection-blender>.

Primary Examiner — Ricky Pham(74) *Attorney, Agent, or Firm* — Banner & Witcoff, Ltd.(57) **CLAIM**

The ornamental design for a blender, as shown and described.

DESCRIPTION

FIG. 1 is a front perspective view of a blender showing my new design;

FIG. 2 is a front view thereof;

FIG. 3 is a rear view thereof;

FIG. 4 is a right side view thereof;

FIG. 5 is a left side view thereof; and,

FIG. 6 is a top view thereof.

The broken lines depicting the remainder of the blender form no part of the claimed design.
